W. J. SCHLOSSER

TENNIS GAME BOARD

Filed Oct. 18, 1926

INVENTOR
WILLIAM J. SCHLOSSER
BY *Munn & Co.*

ATTORNEY

UNITED STATES PATENT OFFICE.

WILLIAM J. SCHLOSSER, OF SAN ANTONIO, TEXAS.

TENNIS GAME BOARD.

Application filed October 18, 1926. Serial No. 142,455.

My invention relates to game boards, and a purpose of my invention is the provision of a game board which simulates a tennis court and in conjunction with game pieces 5 provides means by which two or more persons can play a game requiring a high degree of skill and corresponding in many respects to tennis.

I will describe only one form of game 10 board embodying my invention, and will point out the novel features thereof in claims.

The accompanying drawing is a view 15 showing in perspective one form of game board embodying my invention.

In the drawing the board is designated generally at B, and is constructed of any suitable material and in any desired manner to produce a flat surface over which game pieces such as the disk 15 are adapted to be 20 projected by manipulation of the fingers of the hand. The board is preferably secured within and surrounded by a rectangular frame designated at F and having an up-standing flange 16 projecting above the 25 surface of the board and for the purpose of preventing the accidental displacement of the game pieces from the board. The inner side of this frame is preferably covered with felt, indicated at 17, in order to give the necessary 30 finish to the game board and to render the striking of the game pieces against the flange practically noiseless.

The surface of the game board is provided with lines thereon painted, printed or formed 35 by grooving the surface of the board, or in any suitable manner to render the lines permanent. Longitudinal and transverse lines 18 and 19, respectively, cooperated to define the limits of a court, and by means of 40 other lines 20 spaced from and parallel to the lines 18 and connecting the lines 19 alleys 21 are provided. The court between the alleys is divided into back courts 22 and right and left service courts 23 and 24, all 45 by means of transverse lines 25, 26 and 27 and a longitudinal line 28. At spaced intervals along the line 26 are pegs 27, preferably covered with rubber or some other suitable resilient material for the purpose of 50 protecting the game pieces against injury and aiding the pegs in deflecting the game pieces as they are shot across the board.

As previously described, the game pieces 55 are shown as of disk form and to accom-

modate these game pieces on the surface of the board for a purpose to be hereinafter explained, the outer corners of the service courts have their surfaces provided with pockets 29.

In playing the game a player places one 60 of the game pieces upon the board at the back of either base line 19, and by a flicking of the finger the game piece can be projected 65 forwardly across the surface of the board to the courts of his opponent at the opposite side of the row of pegs 27, it being understood 70 that the pegs correspond to the net in a tennis court. In the actual playing of the game a player "serves" a game piece in the manner described, it being his object to cause 75 the game piece to come at rest in the pocket of the diagonal service court or at least to cause it to remain within the confines of the service court. It will be appreciated that considerable skill is required to project the 80 game piece so as to come at rest within the opponent's service court as in doing so it is necessary that a certain amount of propelling force be exerted on the game piece and sufficient accuracy exercised to avoid the 85 game piece striking the pegs 27. If the game piece strikes any one of the pegs it may be called a "net" and the player loses his service. If the game piece is projected into the pocket 29 a certain count will be made to 90 the credit of the player, but if it comes to a standstill within the service court his opponent, by a similar manipulation of the finger, attempts to project the game piece to the first player's service court or to any 95 point to the opposite side of the pegs 27. In this manner a game piece may be projected by the players to and from their respective service courts until the game piece is projected beyond the confines of the service courts 100 or into the alleys or back courts, when the player making such a projection of the game piece loses a point in the scoring of the game.

I do not wish to be restricted to the precise method of playing the game as it will be understood that various modes of playing may be employed.

Although I have herein shown and described only one form of game board embodying my invention, it is to be understood 105 that various changes and modifications may be made therein without departing from the

spirit of the invention, and the spirit and scope of the appended claims.

I claim:

1. A game board having demarcations defining right and left service courts, back court and alleys, pockets in the service courts adapted for the reception of game pieces, and a series of pegs extending across the board and dividing the right and left hand service courts, said pegs being spaced from each other to provide restricted passages therebetween through which the game pieces are adapted to be projected.
2. A game board having demarcations defining on the surface thereof service courts, pockets in the service courts adapted for the reception of game pieces, and a series of upstanding projections dividing the service courts and being spaced apart from each

other to provide restricted passages therebetween through which the game pieces are adapted to be projected.

3. A game board having demarcations defining on the surface thereof service courts, pockets in the service courts adapted for the reception of game pieces, a series of upstanding projections dividing the service courts and being spaced apart from each other to provide restricted passages therebetween through which the game pieces are adapted to be projected, and a frame surrounding the board and having an upstanding flange to retain the game pieces against accidental displacement from the board.

4. A game board as embodied in claim 2, wherein the pockets are positioned adjacent the outer corners of the service courts.

WILLIAM J. SCHLOSSER.
